(57) **CLAIM**

The ornamental design for a dryer attachment as shown and described.

DESCRIPTION

FIG. 1 is a front, right, top perspective view of the claimed design shown coupled to an appliance and particularly a dryer appliance;

FIG. 2 is a front, right, bottom perspective view of the claimed design of FIG. 1 with the appliance removed;

FIG. 3 is a right, bottom perspective view of the claimed design of FIG. 1 with the appliance removed;

FIG. 4 is a rear, right, top perspective view of the claimed design of FIG. 1 with the appliance removed;

FIG. 5 is a bottom view of the claimed design of FIG. 1 with the appliance removed;

FIG. 6 is a rear, bottom perspective view of the claimed design of FIG. 1 with the appliance removed;

FIG. 7 is a top view of the claimed design of FIG. 1 with the appliance removed;

FIG. 8 is a left side view of the claimed design of FIG. 1 with the appliance removed;

FIG. 9 is a right side view of the claimed design of FIG. 1 with the appliance removed;

FIG. 10 is a front side view of the claimed design of FIG. 1 with the appliance removed, and,

FIG. 11 is a rear side view of the claimed design of FIG. 1 with the appliance removed.

The evenly dashed broken lines in FIG. 1 depict environmental subject matter, specifically a dryer appliance, and forms no part of the claimed design. The evenly dashed broken lines in FIGS. 2–11 illustrate portions of the dryer attachment that form no part of the claimed design. Broken lines formed of unequal length dashes (i.e., dash-dot) show
